HINGED FLOOR RACK

Roland J. Olander, Chicago, Ill., assignor to W. H. Miner, Inc., Chicago, Ill., a corporation of Delaware

Application December 23, 1939, Serial No. 310,730

6 Claims. (Cl. 16—163)

This invention relates to improvements in hinged floor racks for refrigerator cars, and more particularly to the hinged sections thereof which are located at the door openings of the car.

In railway practice, refrigerator cars are provided with floor racks to support the lading raised above the floor of the car, the racks being composed of sections which are foldable against the walls of the car to clear the floor for lading which does not require elevation from the floor. The sections of the rack at the side door openings are arranged to be either folded on top of the adjacent sections to clear the floor of the door opening to permit trucking of the lading into the car, or folded against the underneath sides of said adjacent sections when the rack is folded against the side wall of the car.

The main object of my invention is to provide simple, efficient, and durable means for connecting adjacent sections of a floor rack for refrigerator cars so that one of said adjacent sections may be folded against the other, either on top of or beneath the latter as desired.

Another object of the invention is to provide simple and efficient hinge means for connecting adjacent sections of a floor rack so that one of said sections may be folded against the other either on top of or beneath the latter, wherein the hinge means comprises cooperating hingedly connected arms or links pivoted to the rack sections respectively.

A further object of the invention is to provide hinge means of the character set forth in the preceding paragraph, wherein the hinge arms or links are pivotally connected to base plate members secured to the rack sections respectively, and so designed as to require only one securing element for each plate to mount the same on the rack section and anchor it in place.

Yet another object of the invention is to provide a hinge means for connecting adjacent sections of a floor rack comprising hingedly connected links or arms pivotally mounted on base plate members secured to the rack sections, wherein the base plate members are provided with stop means for limiting the swinging movements of the arms about their pivots to limit the pivotal movement of said arms with respect to the rack sections and thereby keep the hinging movement of the arms with respect to each other under proper control.

Other objects of the invention will more clearly appear from the description and claims herein-after following.

In the drawings forming a part of this speci-

fication, Figure 1 is a top plan view of two adjacent sections of a floor rack, illustrating my improvements in connection therewith, said rack sections being shown partly broken. Figure 2 is an edge elevational view, on an enlarged scale, of the structure shown in Figure 1, looking upwardly in said last named figure, both rack sections being shown partly broken away. Figure 3 is a view similar to Figure 2 but showing one rack section folded beneath the adjacent section. Figure 4 is a view similar to Figure 2 but showing one rack section folded on top of the adjacent section. Figure 5 is a vertical sectional view corresponding substantially to the line 5—5 of Figure 2, showing the hinge means at one side of said racks only, the rack sections being shown broken away at opposite sides of the hinge means. Figure 6 is a vertical sectional view, on an enlarged scale, corresponding substantially to the line 6—6 of Figure 3, the rack sections being shown broken away.

In said drawings, 10 indicates a rack section of conventional form of the type which is ordinarily located at one side of the door opening of the side wall of a refrigerator car, and 11 indicates the usual section which occupies a portion of the space confronting and in line with the door opening. As is well known by those skilled in this art, the usual practice is to divide the portion of the floor rack which occupies the floor space between the transversely aligned side door openings of a refrigerator car, both centrally in a direction transverse of the car and centrally in a direction lengthwise of the same, and swingingly connecting the sections at opposite sides of said space between the doors to the sections of the rack located immediately adjacent said door openings. As is further well known, to clear the floor of the car to convert the car for lading which does not require elevation from the floor, the sections immediately adjacent the door opening of the car, which correspond to the section 10, are foldable respectively against the side walls of the car, and the sections which normally occupy the space between the door openings and correspond to the section 11 are foldable against the underneath sides of said first named sections.

To clear the floor space between the door openings of the car for trucking, it is the common practice to fold the sections which occupy said space on top of the sections adjacent said space and beyond the door openings.

The rack sections 10 and 11 illustrated in the drawings, which sections, as hereinbefore stated

are of conventional design, are composed of longitudinal stringers 12-12-12 and transverse spaced slats 13-13 supported on and secured to said stringers. As shown in Figure 1, each section 10 and 11 of the rack has the stringers 12-12-12 thereof so arranged that two of said stringers are located at opposite sides of the rack and the remaining stringers are located at suitable spaced intervals between said side stringers. The stringers 12 of the two rack sections 10 and 11 are staggered with respect to each other, so that when the section 11 is folded underneath the section 10 the stringers of the two rack sections will lie side by side and thus not interfere with the proper folding of said sections.

As shown in Figure 1, the side stringers 12-12 of the rack section 11 are spaced laterally inwardly with respect to the side stringers 12-12 of the rack section 10, the spacing between the adjacent stringers of the respective racks 10 and 11 being such as to accommodate connecting hinge means therebetween, which hinge means is secured to the inner and outer sides of said stringers.

My improved means for pivotally connecting the rack sections comprises broadly a plurality of hinge members, each comprising a pair of pivotally connected hinge arms or links A-A; a pair of supporting base members B-B on which the hinge arms are pivoted; and a pair of securing elements C-C for said base members.

The hinge arms or links A-A are of similar design, except as hereinafter pointed out. Each arm A comprises an elongated, substantially straight, shank portion 14 and a relatively short section 15 at the outer end of the shank portion, disposed at approximately right angles to said shank portion. At their inner ends, the shank portions 14-14 are enlarged to provide bearing members 16-16 of substantially circular outline. The bearing head portion 16 of each shank 14 is provided with a relatively large bearing opening 17 therethrough. The outer end of the section 15 of each hinge arm is preferably rounded off, as shown, and said outer end of the section 15 of the arm secured to the rack section 11 is provided with a laterally projecting bearing boss 18 which is of smaller diameter than said rounded end, as clearly shown in Figure 5. The outer end of the section 15 of the other arm A of the hinge, which is secured to the rack section 10, is provided with a relatively large bearing opening 19 receiving the bearing boss 18, thereby pivotally connecting the arms A-A. The pivotal connection thus provided for said arms A-A is held together by a rivet 20, or any other similar securing element, extending through a central opening 21 of the boss 18 and the arm A which carries said boss. A washer 22 is preferably interposed between the outer end of the boss 18 and the head at the corresponding end of the rivet. In this connection it is pointed out that the boss 18 is of a length greater than the thickness of the pivoted end of the section 15 of the arm which is mounted on the rack section 10, thereby assuring freedom of movement of the pivotal connection between said arms A-A.

The supporting base members B-B are of similar design, each comprising a fan or sector-shaped plate having oppositely projecting, aligned, outer and inner, cylindrical sleeve members 23 and 24 thereon at the contracted end of the sector. The outer sleeve 23 is shorter than the sleeve 24, as most clearly shown in Figure 6, and serves as a pivot boss or trunnion for the

corresponding arm A, said sleeve being accommodated within the pivot opening 17 of said arm. On the inner side the sector-shaped plate of the member B is provided with a laterally projecting, hollow lug 25. This lug is eccentric to the pivot sleeve 23 and spaced radially therefrom and serves as an anchor for said member B, as hereinafter pointed out. The outer side of the broad portion of the member B is provided with spaced, radially disposed, stop lugs 26-26 for a purpose hereinafter pointed out.

As shown in Figure 2, the base members B-B are secured to adjacent stringers 12-12 of the rack sections 10 and 11 with the broad portions of the sector-shaped plates of said members depending, the sleeve 24 of each base member being seated in a suitable opening 27 extending entirely through the corresponding stringer, and the lug 25 seated in a recess 28 provided in the stringer, the lug 25 holding the base member against rotation about the axis of the sleeve 24.

The base member B is secured in place by the fastening element C, which, as shown, is preferably in the form of a bolt extending through the sleeve members 23 and 24. A washer 29 is interposed between the head 30 of the bolt and the outer end of the sleeve member 23, and a second washer 31 is interposed between the nut 32 and the adjacent side of the stringer 12. As shown in Figure 6, the sleeve member 24 does not extend entirely through the opening 27, sufficient clearance being left between the outer end of said sleeve and the washer 31 to permit the sleeve to be drawn tightly into said opening when the nut 32 is tightened, thereby forcibly drawing the plate section of the base member B against the stringer 12 to securely clamp the base member to said stringer. The sleeve member 23 is of a length greater than the thickness of the bearing portion 16 of the arm or link A and thus projects beyond the outer side of the arm to provide clearance between the bearing head portion 16 and the washer 29, thus assuring freedom of swinging movement of the arm A with respect to the supporting bracket B.

As shown clearly in Figure 1, two sets of hinge members are preferably provided for connecting each set of rack sections 10 and 11, the sets being respectively at opposite sides of said sections. As shown in Figure 2, the parts of each set of hinge members are connected to each other and the sections 10 and 11 of the rack in such a manner that the arms or links A-A rest on the stop lugs 26-26 of the base members B-B, which are nearest the opposed ends of said rack sections. The arms or links A-A are thus positively supported with the hinged connection between said arms in such a position that it will function properly at all times without any danger of binding when the rack section 11 is swung to fold the same either on top of or beneath the section 10. In this connection it is pointed out that by forming each base member B with two lugs 26-26, the base members are made universal for application to either of the rack sections 10 and 11 without modification. In folding the rack section 11 beneath the section 10 the same is swung from the position shown in Figure 2 to the position shown in Figure 3 and the links or arms A-A will assume approximately the position shown in said last named figure.

In folding the rack section 11 on top of the section 10 to clear the door opening of the car, it is swung upwardly from the position shown in Figure 2 over the section 10, to the position shown

in Figure 4, and the links or arms A—A will assume the position shown in said last named figure.

I have herein shown and described what I now consider the preferred manner of carrying out my invention, but the same is merely illustrative and I contemplate all changes and modifications that come within the scope of the claims appended hereto.

I claim:

1. In a floor rack composed of horizontally disposed, separate adjacent sections, the combination with hinge means connecting said sections comprising a pair of arms pivotally connected to each other at one set of ends, said arms having the other ends thereof pivotally connected to said rack sections respectively, said pivotal connections all swinging about horizontal axes; of stop means on said rack sections for limiting downward swinging movement of said arms to maintain the same raised above the lower limits of said sections with the pivotal connection of said arms positioned to accurately guide swinging movement of one rack section on top of the other.

2. In a floor rack including adjacent pairs of horizontally disposed sections, the combination with hinge means including pivotally connected hinge arms for connecting said sections of each pair for folding one of the sections of said pair on top of or beneath the other, the pivotal connection between said arms swinging about a horizontal axis; of supporting means on said rack sections pivotally supporting said arms for swinging movement about horizontal axes at the ends thereof remote from their pivotal connection with each other; and stop members on said rack sections engaging beneath said arms for limiting swinging movement of each of said arms in downward direction with respect to the rack section to which it is connected to support the pivotal connection of said arms with each other in a predetermined position for controlling relative swinging movement of said arms during folding movement of said sections one on top of the other.

3. In a hinge connection for a pair of horizontally disposed floor rack sections, the combination with a pair of links pivotally connected to each other at one set of ends for swinging movement in vertical planes; of supporting members secured to said racks respectively for pivotally supporting the remaining set of ends of said links for swinging movement in vertical planes, each supporting member having a stop thereon engageable underneath the corresponding link to limit downward swinging movement thereof and thereby support the links with the pivotal connection thereof with each other in

position to assure accurate folding of one rack section on top of the other.

4. In hinge means for connecting two horizontally disposed floor rack sections including stringers, the combination with a hinge support secured to each stringer, said support including a vertically disposed platelike portion bearing on one side of the corresponding stringer, a horizontally disposed cylindrical sleeve projecting from the inner side of said plate into the stringer, and a horizontal pivot member projecting from the outer side of said plate; of anchoring means extending through said cylindrical sleeve for clamping the hinge support to the stringer; a link pivotally supported at its inner end on the pivot member of each support for swinging movement in a vertical plane; and means pivotally connecting the outer ends of said links to each other for relative swinging movement about a horizontal axis.

5. In hinge means for a pair of rack sections including supporting stringers, the combination with a pair of pivotally connected links having bearing openings at the ends thereof remote from their pivotal connection; of a pair of supporting members for said links mounted on the stringers of said rack sections respectively, each supporting member including a hollow sleeve extending into and partly through the corresponding stringer and projecting from one side of said stringer, said projecting portion of the sleeve forming a bearing element engaged within the bearing opening of the corresponding link; and a flange on said sleeve between said link and said side of the stringer, and means extending through said sleeve having shouldered engagement with the projecting end of the sleeve and the side of the stringer opposite to said first named side for clamping the supporting member to the stringer.

6. In hinge means for pivotally connecting two adjacent rack sections including supporting stringers, the combination with a pair of pivotally connected links; of means for hingedly connecting the ends of said links, remote from the pivotal connection thereof, to said racks respectively including duplicate supporting members fixed to the stringers of said racks respectively, each supporting member including a plate having a bearing projection thereon journaled in the corresponding link, each of said plates having a pair of spaced stop lugs thereon below said projection, to the right and left of the same, said lugs being radial to the axis of pivotal movement of the link on the projection, the right lug of one of said supporting members and the left lug of the other supporting member limiting swinging movement of said links respectively.

ROLAND J. OLANDER.
